UNITED STATES PATENT OFFICE.

RAY W. BLATZ, OF WILKES-BARRE, PENNSYLVANIA.

ELEVATOR-GATE OPERATOR.

1,184,610.

Specification of Letters Patent.

Patented May 23, 1916.

Application filed April 10, 1915. Serial No. 20,541.

To all whom it may concern:

Be it known that I, RAY W. BLATZ, a citizen of the United States, residing at Wilkes-Barre, in the county of Luzerne and State 5 of Pennsylvania, have invented certain new and useful Improvements in Elevator-Gate Operators; and I do hereby declare the following to be a full, clear, and exact description of the invention, such as will enable 10 others skilled in the art to which it appertains to make and use the same.

This invention relates to elevators, and more especially to the door or gate mechanism employed at the landings of the elevator shaft; and the object of the invention is to produce improved means for automatically opening and closing the gates or barriers by the movements of the elevator.

The invention especially contemplates the 20 application of this general idea to the gates on each floor or level in a mine, and particularly one in which the elevators are built in pairs so that as one ascends the other descends, although I do not wish to 25 be limited to this use of my invention as the same is applicable to elevators of any type.

The invention also includes certain specific structures for carrying out the general idea, all as hereinafter more fully described 30 and claimed and as shown in the drawings wherein—

Figure 1 is a front elevation of this invention as employed at one landing of an elevator shaft having a single elevator; and 35 Fig. 2 is a side view of the same. Fig. 3 is a front elevation of the invention as employed at one landing of an elevator shaft having twin elevators; Fig. 4 is a side elevation of the same; Fig. 5 is a partial plan view; and Fig. 6 is a perspective detail of parts thereof on an enlarged scale. Figs. 40 7, 8 and 9 are diagrammatic views showing the arrangement and position parts, including the cams, as used on a twin elevator 45 system in mines; and Fig. 10 is an enlarged detail of certain parts which will be employed at the middle landing of the elevator shaft, as hereinafter explained.

In the drawings the letter S indicates 50 the shaft in which on upright guides U moves the elevator E, whose raising and lowering mechanism is herein shown as a hoisting rope H. At each floor or level is

disposed a door or gate G for closing the opening into the shaft S at times when the 55 elevator does not stand opposite, and it will be understood that there may be one of these gates at each side of the elevator shaft. No claim is laid on the parts thus far mentioned, nor on the specific construction of 60 the gate itself although in the present case I have shown gates of the lazy-tong pattern.

Opposite each floor or level and in suitable bearings 1 is mounted a cam-shaft 2 in such manner that it may slide or turn in 65 said bearings, a weight 3 normally sliding this shaft to one extreme position. Carried by the shaft is a cam 4 which projects into the elevator shaft S, and carried rigidly by the elevator E is a track 5 adapted to strike 70 the face of the cam when the latter is moved into the path of the rising or falling track, against the pull of the weight 3.

The exact mechanism for opening and closing the gates G will depend to a considerable extent on the character of the gates, but in Figs. 1 and 2 where I have shown horizontally moving lazy-tong gates, the following mechanism may well be employed: To the uppermost links 10 of the 80 crossed inner links of the two gates is attached a weight 11 movable in guides 12 supported on the framing of the elevator shaft S, and the descent of this weight will close the gates. From the shaft 2 projects 85 a lever or sector 13 from which leads a rope or chain 14 passing over a pulley 15 and connected with said weight. The result is that when the track 5 engages the cam 4 and turns the shaft 2, the rope or chain 14 draws 90 the weight 11 upward and the links 10 cause the gates G to open; but when the track has passed the cam, the descent of the weight closes the gates and restores the cam and cam-shaft to normal position. It 95 should be noted that this mechanism does not call for the use of steam, electric, or other power, and has no springs or complicated details to get out of order or become clogged by particles falling thereon.

For sliding the cam-shaft so that the cam will be in the path of the track, one mechanism is provided upon the elevator and another mechanism on the landing at each side of the elevator shaft. In Figs. 1 and 2 a 105 rock lever 20 is pivoted between its ends at

21 and has its upper end forked at 22 to engage a groove 23 around the shaft 2, and links 24 and 25 lead from pivot points above and below the main pivot 21 to hand levers or handles 26 and 27 at opposite sides of the shaft S and in position to be reached by a person approaching from either direction. Elsewhere in the drawings the connections between these handles 26 and 27 and the cam-shaft may be differently shown, but the essential feature is that these levers or handles permit an operator to slide the shaft in its bearings 1 and against the force of the weight 3.

15 In Fig. 4 is shown a latch mechanism for holding the parts after the operator has slid the shaft as just mentioned. Here the shank 30 of the handle 27^a has a notch 31 adapted to drop over a tumbler or other sharp edge 32 when the handle is drawn upon; and in order to lift it out of latching position a cord or rope 33 is led upward from said shank and over suitable pulleys 34 to a point 35 on the cam. The result is that when the track strikes the cam and the latter moves, it draws on the rope 33 and raises the shank 30 of the handle 27^a so as to disengage this latching or catching mechanism.

30 The cam-sliding mechanism on the elevator is also susceptible of considerable modification. In Fig. 2 I have shown it as consisting of a trip 40 which may be projected by hand or otherwise from the edge of the elevator floor and into the line of shoes 41 mounted on levers 42 and pivotally supported at 43 at points above and below the floor line of the landing or shaft which we are discussing. From the remote ends 40 of the levers 42, cords or ropes 44 lead over proper pulleys 45 and 46, and are attached at 47 to the link 25. The result is that when a person on the elevator projects the trip 40 as the elevator approaches a landing, the trip strikes a shoe and turns its lever 42, which motion is communicated by the cords or ropes to one of the links 25 of the sliding mechanism described above. The same action follows, which is that the cam-shaft 2 is moved so as to throw the cam into the path of the track, and the length of the track will of course be such that as the elevator approaches the landing in either direction the track strikes the cam and turns the shaft 2, to open the gates in the manner already described. If the landing handle be provided with a latch as above mentioned, this latch is tripped by the turning of the cam. Therefore as the elevator 60 passes on in either direction, when the track disengages the cam the parts resume their normal position and the gates are closed. In other words, the mechanism on the landing and that on the elevator are useful only 65 for sliding the cam into line with the track,

but it is the movement of the elevator itself after these parts are in alinement which causes the turning of the cam-shaft and the opening of the gates.

Referring now to Figs. 3 to 9 for the application of this idea to a mine elevator in which we will assume that twin elevators are supported by a single rope H which passes over a pulley or drum at the top of the shaft and is turned in one direction or 70 the other by suitable mechanism as usual—the idea being that one elevator must ascend as the other descends. Also in these views the gates while of lazy-tong structure are so mounted that they open and close vertically, and their weight may be partly counter-balanced, as at W. The arrangement of handles 26 and 27 and their connection with the cam-shaft 2 is slightly different, as also the mechanism connecting the shoes 41' with 75 the link 25'; and the mechanism for projecting the trip 40. In this case the tracks 50 will project on the contiguous sides of the elevators E' and E² and will stand strictly in line with each other as seen in Fig. 9, 80 and a cam 51 will be mounted on a cam shaft 52, preferably in the manner shown in Fig. 6, so that the shaft may rotate in and reciprocate through three contiguous bearings 1. Closely mounted between two 85 90 of said bearings is the hub of a sprocket wheel 53 to which the shaft is connected by a feather key 54 in such manner that it may slide through said hub but will cause its rotation in any position; and the sprocket 100 is connected by a chain belt 55 with a second sprocket wheel 56 on an overhead shaft 57—the construction being such that these sprocket wheels are always in alinement and the chain will never run off. Said overhead 105 shaft is in two parts mounted in suitable bearings, one part 57' being connected with the other by means of a clutch 58 which can be opened by a lever 59 which in turn is 110 swung by drawing on a handle 60 that hangs through the elevator shaft framework between the two gates as best indicated in Fig. 3, whereas the clutch is held normally closed by any suitable means such as the counter-weight 61. This detail is for the 115 purpose of entirely disconnecting the gate-operating mechanism at one side of the shaft, so as to throw what might be called the rear gates R, R' in Fig. 9 out of connection 120 with the mechanism while leaving the front gates F, F' in connection therewith; but as soon as the operator releases his hold on the handle 60, the counter-weight 61 closes the clutch 58 and all gates are thereafter 125 connected with the actuating mechanism. Projecting from each end of the shaft 57, 57' is a lever 62 to which is pivoted a pair of links 63, each having a slot 64 near its outer end loosely engaging a pin 65 in one arm of a bell crank lever 66. The other arm 130

of this lever is connected by a link 69 with the gate. Therefore when the overhead or gate-operating shaft is turned in one direction to a sufficient degree, one gate is opened 5 while the other remains closed; when the shaft is turned so that the lever 62 stands upright, both gates are closed; and when the shaft is turned in the other direction, the other gate is opened. These movements 10 of the shaft are effected by its connection with the cam-shaft through the sprockets and chain described (or any equivalent connections), and the cam 51 is turned in one direction or the other according to which 15 track 50 engages it. However, in the greater percentage of cases the elevators will pass up and down their shafts without touching the cam at all, because it must be remembered that the cams all stand normally out of 20 the line of movement of the tracks on the elevators, and are only thrown into such line when a landing is to be made.

It might possibly happen that difficulty 25 would arise at the middle landing of a mine shaft where the two elevators of a pair pass each other, and accordingly I make provision for this contingency. Referring now more especially to Figs. 7 and 9, it will be seen that the cams 51 for all landings but 30 the middle landing are of such size that they will be struck by the tracks 50 on either elevator E' or E², whereas the cam 51' on the middle landing is of half size so that it will be struck by only one track. The result is 35 that at this point the cam shaft is turned always in one direction, and through the sprockets and chain the overhead shaft 57 is also turned in one direction only. Here the lever 62 is replaced by a rock lever 62' (see Fig. 10), and links 63'-63'' connect its 40 extremities with bell crank levers 66, which latter in turn are connected with the gates in the manner above described. The difference, however, is that the turning of the 45 overhead shaft 57 simultaneously draws on both links which (being without the slots 64) will open both gates at this landing, and also both gates will close when the elevators move away from the landing. It 50 is not objectionable that both gates open at this central landing, because here is where the elevators pass each other and when one stands level with the landing the other will; but the mechanism above described for dis- 55 connecting the rear gates while leaving the operator in control of the front gates is equally useful at this landing, as those familiar with mining conditions will understand.

60 Referring now again to Figs. 4 and 6, the link 25^a is shown as swivelly connected with the cam shaft by means of a yoke 70, and with the handle 27^a by means of a second link 25' and a rock lever 25''; and the 65 handle 26^a is connected with the other end

of the cam shaft by a yoke 70' and a rock lever 26'', the chain from the weight 3 being preferably attached to this lever. In Fig. 6 also the shoes 41' are duplicated above and below the landing we are discussing, each pair being mounted on a shaft 43' which in turn carries a lever 42', and these levers are connected by links 44' with a three-arm lever 45', one arm of which is pivoted at 46' to the link 25'. The action 70 of the device is the same as that described for the single elevator shown in Figs. 1 and 2, excepting that the duplication of the shoes 41' is in order to permit them to be acted on by either of the twin elevators moving in 75 either direction. I might say also that under the laws of some States a positive link connection between various elements of a mining mechanism is required, instead of the cords or ropes 44 described with reference to Figs. 1 and 2. However, I reserve the widest latitude in this respect as it is obviously immaterial what are the details of connection at this point. So also 80 with respect to the means for projecting the trip 40. It may be moved by hand or foot as seen in Figs 3 and 4, it may be connected with one arm of a bell crank lever 47 pivoted at its angle beneath the elevator floor, and from the other arm a rod or wire 48 85 leads upward and is connected with one arm of a rock lever 48' preferably pivoted overhead on the elevator, a handle 49 depending from the other arm thereof to a point within reach of an operator standing on the ele- 90 vator.

With the above construction of parts the 95 operation of this invention is as follows: On the assumption that the structure for the twin elevators is in all substantial respects 100 merely a duplication of the structure for the single elevator (excepting with regard to the middle landing), an operator approaches the shaft and desires to ascend, he signals the engineer in charge of the hoisting mechanism, and awaits a signal in return that his wish will be respected. We will assume 105 that the operator receives such signal and draws upon the handle 27 in Fig. 2 or 27^a in Fig. 4, with the result that the cam 4 or 51 is set in line with the track, and, if the latch mechanism shown in Fig. 4 is employed, the operator may release the handle and the parts will remain in that position. I might 110 here say that the same result would occur 115 if the operator approached from the other side and actuated the handle 26 or 26^a. When now the elevator ascends, its track strikes the cam and causes the partial rotation of the cam shaft, and this through the 120 connections already described opens the gate. The operator may then safely step onto the elevator although the shaft be almost in darkness, and he gives a signal to the engineer, the elevator starts upward, 125 130

and the gates close automatically. On the other hand, when an operator desires to descend and get off at a certain level, he informs the engineer of his wishes and boards 5 the elevator at the surface. The engineer now drops the elevator—rather quickly in mines—and when the operator feels its speed decreasing he knows he is approaching his landing. At this time he projects 10 the trip 40 by any means which are provided on the elevator, with the result that the trip engages one of the shoes 41' and this, through its connection with the link, slides the cam shaft, puts the cam in line with the 15 track, and automatically opens the gate in the manner already described. The same operation takes place at the middle landing where the elevators cross, excepting that the link mechanism shown in Fig. 10 causes the 20 opening of both gates whenever the cam 51' is actuated.

What I claim is:

1. The combination with an elevator, an upright track fixed thereto, a gate across 25 each landing, means for normally closing it, a shaft rotating and sliding in bearings at each landing, a cam fast thereon, and means for sliding the shaft to hold said cam normally out of line with said track; of handles 30 at both sides of the landing, rock levers actuated by the movements of the handles, swivel connections between said levers and the cam shaft, a shoe in the elevator shaft connected with one rock lever, and a trip on the elevator adapted to be manually projected into the path of the shoe. 35

2. The combination with an elevator shaft, gates across both sides of each landing, means for normally closing them, an elevator, a projection thereon, a shaft rotating and sliding in its bearings, connections between it and said gates for opening them when the shaft is rotated, a cam fast on said shaft, and means for normally sliding the 40 shaft in one direction to cause the cam to stand out of line with said projection; of a handle at each landing, connections between it and the cam shaft for sliding the latter by the movement of the handle, a latch for holding the handle in one of its extreme positions, and connections between the latch and cam for disengaging the former from said handle when the cam begins its rotary movement. 45

3. The combination with an elevator, an upright track fixed thereto, a gate across 50 each landing, means for normally closing it, a shaft rotating and sliding in bearings at the landing, and a cam fast thereon standing normally out of line with said track; of a handle at the landing, a link connecting it with said cam shaft, a shoe in the elevator shaft connected with said link, a trip on the elevator adapted to be projected into the 55 path of the shoe, a latch for holding the han-

dle in one of its extreme positions, and connections between the latch and cam for disengaging the former from said handle when the cam begins its rotary movement.

4. The combination with an elevator, an 70 upright track fixed thereto, a gate across each landing, a weight for normally closing it, a shaft rotating and sliding in bearings at each landing, a cam fast thereon, and a weight sliding the shaft to hold said cam normally out of line with said track; of a handle at the landing, a link connecting it with said cam shaft, a shoe in the elevator shaft connected with said link, and a trip on the elevator adapted to be projected into 75 the path of the shoe. 80

5. The combination with an elevator, an upright track fixed thereto, a gate across 85 each landing, means for normally closing it, and mechanism for opening it including a shaft rotating and sliding in its bearings and a cam thereon standing normally out of line with said track; of a handle at the landing for sliding said cam shaft, a shoe in the elevator shaft connected with said cam shaft, and a trip on the elevator adapted to be projected into the path of the shoe. 90

6. The combination with an elevator, an upright track fixed thereto, a gate across 95 each landing, means for normally closing it, and mechanism for opening it including a cam and its shaft rotatably and slidably mounted; of means for normally sliding said shaft in one direction to cause its cam to stand out of line with said track, a handle 100 at the landing for sliding said shaft in the other direction, movable shoes in the elevator shaft above and below the landing, connections between them and said shaft for sliding the latter, and a trip on the elevator adapted to be manually projected 105 into the path of said shoes. 110

7. The combination with an elevator shaft, gates across both sides of a landing, means for normally closing them, an elevator, a projection thereon, a shaft rotating and sliding in its bearings, connections between it and said gates for opening them when the shaft is rotated, a cam fast on 115 said shaft, and means for normally sliding the shaft in one direction to cause the cam to stand out of line with said projection; of a rock lever connected with said cam shaft, and handles at both sides of the elevator shaft connected with said rock lever. 120

8. The combination with an elevator shaft, gates across both sides of a landing, means for normally closing them, an elevator, a projection thereon, a shaft rotating and sliding in its bearings, connections between it and said gates for opening them when the shaft is rotated, a cam fast on 125 said shaft, and means for normally sliding the shaft in one direction to cause the cam to stand out of line with said projection; of 130

handles at both sides of said elevator shaft, links leading from said handles, and a rock lever connected to the links and cam shaft for sliding the latter by the movement of either handle.

9. The combination with an elevator shaft, gates across both sides of a landing, means for normally closing them, an elevator, a projection thereon, a shaft rotating and sliding in its bearings, connections between it and said gates for opening them when the shaft is rotated, a cam fast on said shaft, and means for normally sliding the shaft in one direction to cause the cam to stand out of line with said projection; of handles at both sides of said elevator shaft, links leading from said handles, connections between the links and cam shaft for sliding the latter by the movement of either handle, a latch for holding one handle in one of its extreme positions, and connections between the latch and cam for disengaging the former from said handle when the cam begins its rotary movement.

10. The combination with an elevator shaft, gates across both sides of a landing, means for normally closing them, an elevator, a projection thereon, a shaft rotating and sliding in its bearings, connections between it and said gates for opening them when the shaft is rotated, a cam fast on said shaft, and means for normally sliding the shaft in one direction to cause the cam to stand out of line with said projection; of handles at both sides of said elevator shaft, links leading from said handles, connections between the links and cam shaft for sliding the latter by the movement of either handle, one of said handles having a notch in its lower edge, a fixed element with which said notch engages when this handle is moved to one of its extreme positions and dropped, and a cord led from this handle to said cam and drawn upon to raise the handle when the cam turns.

11. The combination with an elevator shaft having a normally closed gate at each landing, an elevator having a projection, a shaft rotating and sliding in its bearings, a cam fast on the shaft and adapted to be turned when struck by said projection, means normally sliding the shaft to hold the cam out of the path of the projection, and connections between the shaft and gate for opening the latter when the shaft turns; of a link swiveled to said cam shaft, a handle whose shank is pivotally connected with said link and provided with a notch in its lower edge, a fixed element with which said notch engages when the handle is drawn outward and dropped, a cord leading from the handle to said cam, and pulleys over which the cord passes.

12. The combination with an elevator shaft having a normally closed gate at each

landing, an elevator having a projection, a shaft rotating and sliding in its bearings, a cam fast on the shaft and adapted to be turned when struck by said projection, means normally sliding the shaft to hold the cam out of the path of the projection, and connections between the shaft and gate for opening the latter when the shaft turns; of a link swiveled to said cam shaft, a handle whose shank is pivotally connected with said link and provided with a notch in its lower edge, a fixed element with which said notch engages when the handle is drawn outward and dropped, a cord leading from the handle pulleys over which the cord passes to the cam, levers pivoted in the elevator shaft above and below the landing and carrying shoes, a trip on the elevator adapted to be manually projected so as to engage said shoes, and means connecting said lever with said link for drawing on the latter when the trip strikes either shoe.

13. The combination with an elevator shaft, oppositely moving twin elevators therein, tracks on the elevators projecting toward each other, gates at each landing, and means for normally closing them; of a cam shaft rotating and sliding in bearings between said gates and having a cam, means for normally sliding the shaft to put the cam out of alignment with said tracks manually operable means for sliding said shaft to put the cam into such alignment, and connections between certain of the gates and shaft for opening the former when the latter is rotated.

14. The combination with an elevator shaft, oppositely moving twin elevators therein, tracks on the elevators projecting toward each other, gates at each landing, and means for normally closing them; of a cam shaft rotating and sliding in bearings between said gates and having a cam, means for normally sliding the shaft to put the cam out of alignment with said tracks, manually operable means for sliding said shaft to put the cam into such alignment, an overhead shaft above the landing, connections between it and the cam shaft for causing such shafts to turn in unison, bell-crank levers each having one arm connected with a gate, a lever fast on the overhead shaft, and connections between it and the other arms of the bell-crank levers, for the purpose set forth.

15. The combination with an elevator shaft, oppositely moving twin elevators therein, tracks on the elevators projecting toward each other, gates at each landing, and means for normally closing them; of a cam shaft rotating and sliding in bearings between said gates and having a cam, means for normally sliding the shaft to put the cam out of alignment with said tracks, manually operable means for sliding

said shaft to put the cam into such alignment, an overhead shaft above the landing, connections between it and the cam shaft for causing such shafts to turn in unison, 5 bell-crank levers each having one arm connected with a gate, a lever fast on the overhead shafts, links pivoted at their inner ends to said lever and having their outer ends slotted, and pins in the other arms of

said bell-crank levers engaging said slots, 10 for the purpose set forth.

In testimony whereof I affix my signature in presence of two witnesses.

RAY W. BLATZ.
